UNITED STATES PATENT OFFICE.

AUGUST H. EISENMANN, OF PHILADELPHIA, PENNSYLVANIA.

DEVICE FOR CLEANING AND POLISHING KNIVES, FORKS, AND SPOONS.

1,137,468.

Specification of Letters Patent. Patented Apr. 27, 1915.

Application filed December 6, 1913. Serial No. 805,027.

To all whom it may concern:

Be it known that I, AUGUST H. EISENMANN, a citizen of the United States, residing in the city and county of Philadelphia, State 5 of Pennsylvania, have invented a new and useful Device for Cleaning and Polishing Knives, Forks, and Spoons, of which the following is a specification.

My invention relates to a new and useful 10 improvement in a device for cleaning and polishing knives, forks and spoons, and consists in providing a plurality of cleaning or polishing surfaces with means for locating the same in operative position and means for 15 holding the same in such position.

It further consists of a body portion in pivoted relation to a handle, said body portion having offsets, with a polishing means carried by each off-set and each means having a face different from the faces of the other polishing means.

It further consists of other novel features of construction, all as will be herein-after fully set forth.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of a device for cleaning and polishing knives, forks and spoons, embodying my invention, showing the same in use upon a knife. Fig. 2 represents a vertical sectional view showing the device applied to a spoon and with the proper polishing surface in operative position. Fig. 3 represents an end elevation 45 showing the device in use for cleaning the prongs of a fork.

Similar numerals of reference indicate corresponding parts in the figures.

Referring to the drawings:—1 designates 50 a grasping handle which is of any suitable style or construction, and provided with arms 2 forming a yoke.

3 designates a body portion formed in any suitable or desired manner and adapted for 55 pivotal connection with the arms 2 of the

handle 1, and as here shown, the parts being rotatably connected by means of a rod 4.

5, 6 and 7 designate off-sets from the body portion suitably spaced apart and provided on their outer faces with suitable serrations 60 or roughened portions 8 and one of said off-sets, as here shown, 6, being provided with a recess or seat 9 formed at a suitable point on the ends thereof. To each of the offsets is suitably secured in any desired manner, a 65 polishing or cleaning means, and, as here shown, I have connected with the offset 5 the polishing means 10, which is provided with a flat outer face 11 which forms the operative surface and is adapted for use upon a 70 knife. The offset 6 is provided with a polishing or cleaning means 12 which is provided with a suitably rounded outer face 13 which forms the operative surface thereof and which is adapted for use in cleaning 75 and polishing forks, the same being rounded in order to accommodate itself to the rounded portion of the fork which is formed between the prong and the handle portion, while seated in the recesses 9 is a portion of 80 the polishing or cleansing means forming a V-shaped projecting member 14 spaced from the end 15 of the polishing means 12 and leaving a space 16 therebetween, said space serving to receive one of the prongs of the 85 fork with the projection or projecting portion 14 adapted to pass between the prong and the next adjacent prong. The offset 7 is provided with the polishing and cleansing means 17 which is provided with a suitably 90 rounded out face 18, which is suitably formed in order to properly contact with and clean the bowl of a spoon, the construction being best seen in Fig. 2.

In order to locate the proper polishing or 95 cleansing means in its operative position, I have provided means for permitting rotation of the body portion with respect to the handle and I have provided means for securing the desired polish or cleansing 100 means in operative position. As here shown, I have, at suitable intervals in the body portion, provided openings 19, one in suitable relation with respect to a polishing or cleansing means and I have provided a 105 pin 20 which is supported by or carried by one of the arms 2, as here shown, and which is adapted to enter the proper opening 19 in the body portion for locking the desired polishing means in operative position. It 110

will be understood that by removing the pin 20 from engagement with an opening 19, the body portion 3 can be rotated upon the rod 4 until the desired polishing means 5 is in operative position, after which the pin 20 is inserted in the proper opening 19 for this purpose. The operation of the device from the above will be readily apparent and the device operates in a satisfactory manner 10 with respect to either a knife, fork or spoon.

Supposing the parts to be in the position seen in Fig. 1, the polishing or cleansing means in operative position is adapted for use on a knife and the operator, by 15 grasping the handle 1, can move the device over the knife in order to thoroughly clean and polish the same. Should it now be desired to clean and polish a spoon, the operator will remove the pin 20 from its opening 19 and rotate the body portion 3 until the polishing means 17 is in the position seen in Fig. 2, whereupon the pin 20 is inserted in the proper opening 19 in the body portion and the parts are ready for operation. 20 A similar action is taken when a device for cleaning a fork is desired to be placed in operative position.

It will now be apparent that I have devised a novel and useful construction of a 30 device for cleaning and polishing knives,

forks and spoons, which embodies the features of advantage enumerated as desirable in the statement of the invention and the above description, and while I have, in the present instance, shown and described a preferred embodiment thereof which has been found in practice to give satisfactory and reliable results, it is to be understood that the same is susceptible of modification in various particulars without departing from the spirit or scope of the invention or sacrificing any of its advantages. 35

Having thus described my invention, what I claim as new and desire to secure by Letters Patent, is:—

45 In a device of the character stated, a grasping handle, a body portion in rotative relation to said handle and carrying a plurality of polishing faces, said body portion having a plurality of openings and a locking pin in suitable connection with said handle and adapted to be inserted in the proper opening of the body portion in order to locate the desired polishing face in operative position.

AUGUST H. EISENMANN.
